(57) **CLAIM**

The ornamental design of a tapered sheetrock mud knife with rounded edges, invention as shown and described.

DESCRIPTION

FIG. 1 is a bottom isometric view of a tapered sheetrock mud knife with rounded edges showing my new design.

FIG. 2 is a top view of a preferred embodiment

FIG. 3 is a front view thereof.

FIG. 4 is a bottom view thereof.

FIG. 5 is a right side view thereof.

FIG. 6 is a back view thereof.

FIG. 7 is a left side view thereof; and,

FIG. 8 is a top isometric view with the tapered sheetrock mud blade placed in a tapered mud pan.

The broken lines showing of the tapered mud pan in FIG. 8 is illustrative of environment, and forms no part of the claimed design.
